DESIGN FOR A WHEEL DISK OR SIMILAR ARTICLE

George Albert Lyon, Allenhurst, N. J.

Application June 22, 1936, Serial No. 63,429

Term of patent 14 years

To all whom it may concern:

Be it known that I, George Albert Lyon, a citizen of the United States and a resident of the village of Allenhurst, in the county of Monmouth and State of New Jersey, have invented a new, original, and ornamental Design for a Wheel Disk or Similar Article, of which the following is the specification, reference being had to the accompanying drawing, forming a part thereof.

On the drawing:

Figure 1 is an outer side view of the wheel disk embodying my design.

Figure 2 is an end view of the disk shown in Figure 1.

Figure 3 is a profile view illustrating the external configuration of the design.

I claim:

The ornamental design for a wheel disk or similar article, as shown.

GEORGE ALBERT LYON.
